(57) **CLAIM**

The ornamental design for a drive flange cap, as shown and described.

DESCRIPTION

FIG. 1 is a front perspective view of a drive flange cap, showing our new design;

FIG. 2 is a front view thereof;

FIG. 3 is a side view thereof, it being understood that the opposite side is a mirror image thereof;

FIG. 4 is a front perspective view of a second embodiment of a drive flange cap, showing our new design;

FIG. 5 is a front view of FIG. 4;

FIG. 6 is a side view of FIG. 4, it being understood that the opposite side is a mirror image thereof;

FIG. 7 is a front perspective view of a third embodiment of a drive flange cap, showing our new design;

FIG. 8 is a front view of FIG. 7; and,

FIG. 9 is a side view of FIG. 7, it being understood that the opposite side is a mirror image thereof.

The broken line showing of the side portion of the drive flange cap in FIGS. 3, 6 and 9 is included for the purpose of illustrating environment and forms no part of the claimed design.
